(57) **CLAIM**

The ornamental design for a single portion package comprising a snap opening, as shown and described.

DESCRIPTION

FIG. 1 is a perspective view of a single portion package comprising a snap opening in accordance with one embodiment of the presently disclosed subject matter.

FIG. 2 is a front elevation view of the single portion package comprising a snap opening shown in FIG. 1.

FIG. 3 is a top plan view of the single portion package comprising a snap opening shown in FIG. 1.

FIG. 4 is a bottom plan view of the single portion package comprising a snap opening shown in FIG. 1.

FIG. 5 is a rear elevation view of the single portion package comprising a snap opening shown in FIG. 1.

FIG. 6 is a right side elevation view of the single portion package comprising a snap opening shown in FIG. 1.

FIG. 7 is a left side elevation view of the single portion package comprising a snap opening shown in FIG. 1.

FIG. 8 is a perspective view of a single portion package comprising a snap opening in accordance with one embodiment of the presently disclosed subject matter.

FIG. 9 is a front elevation view of the single portion package comprising a snap opening shown in FIG. 8.

FIG. 10 is a top plan view of the single portion package comprising a snap opening shown in FIG. 8.

FIG. 11 is a bottom plan view of the single portion package comprising a snap opening shown in FIG. 8.

FIG. 12 is a rear elevation view of the single portion package comprising a snap opening shown in FIG. 8.

FIG. 13 is a right side elevation view of the single portion package comprising a snap opening shown in FIG. 8; and,

FIG. 14 is a left side elevation view of the single portion package comprising a snap opening shown in FIG. 8.
